UNITED STATES PATENT OFFICE.

FRED S. GABLE, OF GLENROCK, PENNSYLVANIA.

POSITIVE SHUTTLE-MOTION FOR LOOMS.

SPECIFICATION forming part of Letters Patent No. 714,294, dated November 25, 1902.

Application filed December 16, 1901. Serial No. 36,137. (No model.)

To all whom it may concern:

Be it known that I, FRED S. GABLE, a citizen of the United States, residing at Glenrock, in the county of York and State of Pennsylvania, **5** have invented a new and useful Positive Shuttle-Motion for Looms, of which the following is a specification.

My invention relates to certain improvements in loom-shuttle-operating mechanism **10** of that class employed in wire-weaving looms, and has for its principal object to improve the construction of the shuttle-holding catches for holding and carrying the shuttles across the shed.

15 A further object is to dispense with the employment of catches of that class in which the tensional strain of the wire is resisted directly by a spring-catch, to the end that all danger of the dropping of the shuttle in the shed may **20** be avoided.

With these and other objects in view the invention consists in the novel construction and arrangements of parts hereinafter described, illustrated in the accompanying **25** drawings, and particularly pointed out in the appended claims.

In the drawings, Figure 1 is an elevation of sufficient of a wire-weaving loom to illustrate the construction and application of my improved shuttle-operating mechanism. Fig. 2 is a sectional elevation of one of the shuttle-carrying bars. Fig. 3 is a sectional plan view of the same. Figs. 4 and 5 are views similar to Fig. 3, illustrating modifications of the **35** structure.

Similar numerals of reference are employed to indicate similar parts throughout the figures of the drawings.

The structure of the loom employed in connection with the present invention is immaterial, and the form herein illustrated and described is merely employed as an instance of one form of loom to which the invention may be applied.

45 1 designates a portion of a loom-frame, and 2 a swinging lathe, provided at its upper end with boxes 3 for the reception of a shaft 4, on which the lathe is pivoted, said shaft being supported in bearings 5 on the loom-frame.

50 6 designates a shaft carried by bearings on the loom-frame and rotated by any suitable mechanism. This shaft carries a gear-wheel

7, which meshes with a gear-wheel 8 on a shaft 9, also journaled in the frame and carrying two crank-arms 10, which are connected by rods or arms 11 to brackets 12, arranged at the outer ends of the hollow shuttle-bars 14. The shuttle-bars slide in boxes 15, connected to or supported by the loom-frame, and are moved back and forth by the rotation of the **60** cranks 10.

Pivoted to the brackets 12 at the outer ends of the hollow shuttle-bars are suitable levers 16, adapted to be operated upon in alternation by cam-plates 17, guided upon the loom-frame and adjustably connected to a reciprocated rod 18, which is operated by a lever 19, pivoted at 20 to the frame and adapted to be operated upon by a suitable cam 21, which receives its motion from the shaft 6, bevel-gears 22 and 23, shaft 4, spur-gears 24 and 25, and shaft 26.

The construction and operation of the mechanism thus far described are well known in the art and form no part of my present invention. **75**

The shuttle-bars 14 are rectangular in cross-section and are of sufficient length to carry the shuttle positively through the shed at each operation. The shuttle 30 may be of the usual **80** type, carrying a bobbin for the wire to be woven and provided at each end with an engaging hook 31, adapted to pass within the open end of the shuttle-bar, the latter being preferably provided with flared end portions **85** 32 and the end of the shuttle being slightly inclined in order to facilitate its entrance into the shuttle-bar.

On one side of the shuttle-bar are formed two openings 33 and 34, through which pass **90** the end portions of a catch or hook 35, the body portion of the hook being located outside the shuttle-bar and having a flattened face adapted to fit snugly against the flat outer face of the bar. The hooked end, or **95** that end adapted to engage with the catch or hook of the shuttle, is provided with a rounded outer end 36, adapted to be engaged by the inclined end of the shuttle on its inward movement, and is also provided with a slightly-inclined shoulder 37 for engagement with a correspondingly-shaped shoulder or face on the shuttle. The shank portion of the catch extends through the openings 34 and is mount- **100**

ed on a pivot-pin 38, the ends of which extend through the wall of the shuttle-bar. On the shank portion of the catch are front and rear end faces 40 and 41, respectively, which 5 are engaged by a suitably-shaped cam-block 42, adapted to fit within the shuttle-bar and provided with a recess, into which the shank of the catch extends. The recess is so shaped as to form front and rear cam-faces 43 44 for 10 engagement with the cam-faces 40 and 41, respectively, of the cam-catch 35. The cam-block is connected by a rod 45 to the lever 16, the end of the rod being threaded for the reception of two adjustable nuts 46 47, (shown 15 by dotted lines in Fig. 2,) said nuts holding a collar 48, from which projects a pin 49 into a vertical slot 50, formed in the lever. At a point within the shuttle-bar the rod 45 is provided with a fixed collar 51, between which 20 and the end of the shuttle-bar is a coiled compression-spring 52, normally tending to force the cam-block in the direction of the catch and forcing the cam-face 44 of said block into engagement with the cam-face 41 of the catch, 25 thus tending to keep the hooked end of the catch in position within the lines of the shuttle-bar.

In the operation of the mechanism the shuttle-bars receive movement in opposite direction through the leading of the cranks 10 and connecting-rods 11, the operating-lever 16 being brought into contact with their respective cams 17 at such times as to withdraw one or other of the cam-blocks 42, causing its cam-face 43 to come into contact with the cam-face 40 of the catch, and thus raise the hooked end of the latter from engagement with the hooked end of the shuttle. At the same time the opposite end of the shuttle is forced into 40 the opposite open end of the mating shuttle-bar, coming into contact with the inclined face 36 of the catch and automatically raising the same until it has passed beyond the slightly-inclined face 37 of the hooked end of 45 the catch, the latter being then depressed by the action of the spring 52 as the cam-face 44 is forced against the cam-face 41 of the catch.

The face 37 of the catch and the similar 50 face of the shuttle-hook with which it engages may be perfectly straight or at a right angle to the length of the shuttle-bar, but for convenience are slightly inclined, so that there will be no backward pull on the shuttle as 55 the catch swings on its fulcrum-point to the disengaging position. The inclination of these faces, however, is such that there can be no possibility of their disengagement under the tensional strain exerted by the weft-wires, the cam-faces 44 and 41 being forced 60 into intimate contact under stress of the spring 52 and preventing movement of the hooked end of the catch in an outward direction. By this means I am enabled to insure the firm 65 holding of the shuttle during its travel across the shed, preventing the disengagement of the shuttle from the carrying-catch by reason

of the tension of the wire, and at the same time the construction is such as to have all of the working parts inclosed within the body 70 of the shuttle-bar, avoiding any projections which might engage with the warps.

The structure may be slightly modified in the manner shown in Fig. 4, the hook 35' in this instance being fulcrumed on a pin 38' 75 within the body of the shuttle-bar and from thence extending rearwardly to form a lever 53 for engagement with the operating-bar 45', the latter being provided with a compression-spring and cam-operated lever in the manner 80 previously described.

In Fig. 5 I have illustrated a further modification in which the hook or catch 35" is pivoted at 38" and is connected by a link 60 to a block 61, guided within the shuttle-bar and 85 connected by a rod 45' to an operating-lever and spring of the character above set forth.

In both of the modified constructions it will be noted that the mechanism is also contained within the limits of the shuttle-bar and that 90 the construction is such that there can be no disengagement of the shuttle-catch under tensional strain of the wire.

The structure may be modified in a variety of ways as regards form, proportions, and 95 minor details of construction without departing from the intent or spirit of my invention, and it may be applied to positive shuttle-motion looms of any desired character or construction.

Having thus described my invention, what I claim is—

1. In a device of the class specified, the combination with a hollow shuttle-bar, of a catch or hook having its shank end extending through an opening into the body of the bar and pivoted therein and its engaging or bill end extending through a second opening in the bar, an operating-lever arranged at the outer end of the bar, and means for moving 105 said lever to positively operate the catch or hook in both opening and closing movements, substantially as specified.

2. In a device of the class specified, the combination with a hollow shuttle-bar, of a cam-block guided therein and having a recess, a shuttle catch or hook having its shank end extending into said recess and pivoted to the shuttle-bar, said catch having cam-faces for engagement with cam-faces on the block, an 110 operating-lever arranged at the outer end of the shuttle-bar, a rod connecting the lever and block, and a compression-spring arranged on said rod and normally tending to hold the catch in closed position, substantially as specified.

3. In a device of the class specified, the combination with a hollow shuttle-bar having outwardly-flared walls at its inner end, a cam-block guided within the shuttle-bar and having a recess, a shuttle-engaging hook or catch having its engaging and shank ends extending through openings in one wall of the bar, the shank end having cam-faces adapted for

engagement with similar cam-faces on the cam-block, a pivot-pintle for securing said shank end to the body of the bar, an operating-lever arranged at one end of the bar, an 5 operating-rod extending from the lever to the cam-block, means for adjusting the relative positions of the lever and rod, a fixed collar carried by the rod at a point within the shuttle-bar, and a coiled compression-spring sur-

rounding said rod and extending between the 10 collar and the end of the shuttle-bar.

In testimony that I claim the foregoing as my own I have hereto affixed my signature in the presence of two witnesses.

FRED S. GABLE.
